UNITED STATES PATENT OFFICE

PHILIP E. MEANEY, OF WORCESTER, MASSACHUSETTS, ASSIGNOR TO DAVID E. SHERIN,
OF WORCESTER, MASSACHUSETTS

FLUSH TANK

Application filed May 25, 1931. Serial No. 539,759.

This invention relates to a flush-tank such as is commonly used in connection with toilets.

It is the general object of my invention to improve the construction of such tanks by providing improved valve mechanism so designed that the flush-tank will be more reliable in operation and more satisfactory for its intended purposes.

Particular features of the invention relate to the provision of an improved inlet valve and float-control therefor, and to the provision of an improved outlet valve particularly designed to avoid noise in the emptying of the tank.

A preferred form of the invention is shown in the drawings, in which

Fig. 1 is a sectional side elevation of my improved tank;

Fig. 2 is a plan view thereof;

Fig. 3 is an enlarged sectional elevation of the discharge or outlet valve, taken along the line 3—3 in Fig. 2;

Fig. 4 is a transverse sectional view of the discharge valve casing, taken along the line 25 4—4 in Fig. 3, and

Fig. 5 is an enlarged side elevation of the inlet valve, partly in section, and looking in the direction of the arrow 5 in Fig. 2.

Referring to the drawings, I have shown a tank 10 which may be of any usual construction and which may be formed of any suitable material. The tank 10 is provided with an inlet pipe 11 and with a discharge pipe 12. The inlet pipe 11 extends downward toward the inner bottom of the tank, as indicated in Fig. 1, and the extreme lower end of the pipe 11 may be reduced in cross section, as indicated at 13 in Fig. 5.

A threaded sleeve 15 is loosely slidable on the downwardly extending portion of the pipe 11 and a cap or head 16 is tightly threaded on the lower end thereof. A chamber 18 is provided in the cap 16, and the lower end portion of the cap is closed by a plug 20 having a packing 21 of leather or other suitable material seated in a recess 22 in its upper face. Slots or openings 23 are provided in the cap 16 to permit the escape of water from the chamber 18.

A collar 25 (Fig. 5) is threaded on the sleeve 15 and is provided with upstanding ears 26, connected by links 27 to arms 28 fixed in a rock shaft 30 which is pivotally mounted in the tank 10. A U-shaped frame 32 (Fig. 55 2) has the ends thereof firmly secured in the rock shaft 30, with portions of the frame extending along the sides of the tank and also across the end thereof remote from the rock shaft 30.

A cylindrical float 33 is provided with a plurality of ears or brackets 34 through which the side portions or legs of the frame 32 extend. The legs of the frame 32 preferably converge toward the rock shaft 30, thus preventing displacement of the float toward the rock shaft when the device is in use. The ears 34 may be additionally secured to the frame 32 by solder or brazing, if so desired.

The threaded sleeve 15 will be so adjusted 70 in the collar 25 that when the float 33 is raised by the water to the desired upper water level, the packing 21 will be firmly seated against the lower end of the lower portion 13 of the inlet pipe 11. When the water level in the tank falls, the downward movement of the float will release the upward pressure on the sleeve 15 and the packing 21, permitting these parts to move downward and allowing water to enter the tank through the chamber 18 and slots 23.

By adjusting the sleeve 15 in the collar 25, the float level may be changed to vary the amount of water used each time the tank is emptied.

My improved supply valve and the float control therefor is simple and substantial in construction, is easily adjusted, and is extremely reliable in operation, as the float is firmly attached by two arms to the rock shaft 30 and no adjustment of the float or bending of the frame 32 is ever necessary to adjust the water level or to vary the seating of the packing 21 against the lower end of the supply pipe. If the packing 21 becomes worn it may be very readily replaced by unscrewing the plug 20.

In Figs. 3 and 4 I have shown the details of construction of my improved outlet or discharge valve. A valve casing 40 is seated

- in an opening 41 (Fig. 3) in the bottom of the tank 10. The casing 40 is provided with an outwardly enlarged sleeve-like upper extension 42 which provides a shoulder 43 adapted to be seated against a suitable packing 44. The lower end of the casing 41 is threaded to receive a clamping nut 45 by which the casing may be secured in position. The discharge pipe 12 may be connected in 10 any convenient manner to the lower end of the casing 40 as by being threaded into a bushing 46 which in turn is threaded into the lower end of the nut 45 and is seated against the lower end surface of the casing 40.
- 15 The casing 40 is also provided with an up-standing annular flange 48 forming a valve seat, and with a plurality of ports or openings 49 through which water may flow to the discharge pipe 12 when the outlet valve is open.
- 20 A plunger 50 is guided at its upper end in a bracket or bearing 51 (Fig. 1) mounted on the side of the tank 10. A cup-shaped member 52 is mounted on the lower end of the plunger 50 and a suitable packing ring 53 is seated in the member 52 and is retained in position by a nut 54, threaded on the reduced lower end of the plunger 50. The member 52 is quite loosely slidably in the sleeve portion 42 of the casing 40 and the packing 25 53 is seated against the upper end of the annular flange 48. The packing 53 may be of leather, rubber or any other suitable packing material.
- 30 A coil spring 55 on the plunger 50 engages the bearing 51 at its upper end, and at its lower end engages a collar 56 secured on the plunger 50. The spring 55 acts to depress the plunger 50 and to hold the packing 53 normally seated against the annular flange 48.
- 35 The upper end of the plunger 50 is slotted to receive the end of an actuating lever 60, pivoted at 61 to an arm 62 secured to the bracket 51. The lever 60 has a pin and slot connection with the plunger 50 and may be 40 actuated by the usual pull chain 63 or in any other convenient manner. When the chain is pulled, the plunger 50 is raised, permitting water to enter the sleeve 42 through the ports 49 and to escape downward through the discharge casing 40 and discharge pipe 12.
- 45 I have made special provision for silencing the water as it flows downward through the outlet valve. For this purpose I provide a transverse partition 70 (Fig. 3) extending across the discharge casing 40 from one side to the other thereof and having its upper end portion slotted to provide a series of tongues 72, which are bent alternately in opposite directions, as clearly shown in Fig. 4.
- 50 In actual operation it has been found that the provision of the partition 70 with the oppositely disposed upward extensions or tongues 72 breaks up the flow of water through the discharge casing 40 in such manner that the usual whirlpool or suction effect

is entirely prevented. The objectionable noise commonly noted when a tank is being emptied is thus eliminated. The tongues 72 are preferably disposed at an angle of substantially sixty degrees with respect to each other.

The plunger 50 is preferably tubular and has an opening 80 near its upper end to serve as an overflow outlet.

It will be readily apparent that all parts of the discharge valve, as well as of the inlet valve, are of substantial and rugged construction and are well adapted to give long service without repairs or replacements. If it is desired to replace the packing 53, this may be readily done by removing the plunger 50 and loosening the nut 54.

All parts of the mechanism may be easily and quickly assembled or removed, reducing the cost of repairs.

Having thus described my invention and the advantages thereof, I do not wish to be limited to the details herein disclosed, otherwise than as set forth in the claims, but what I claim is:—

1. In a flush tank, an outlet valve having a discharge passage, and a partition member mounted in said passage and extending diametrically across said passage and lengthwise in the line of flow, said partition member having offset lugs disposed along an edge of said partition extending crosswise of said discharge passage, and said partition member and offset lugs substantially eliminating noise when the tank is emptied through said valve by obstructing the whirling motion of the water.

2. In a flush tank, an outlet valve having a discharge passage, and a partition member mounted in said passage and extending diametrically across said passage and lengthwise in the line of flow, said partition member having offset lugs along its upper edge, and said partition member and offset lugs substantially eliminating noise when the tank is emptied through said valve.

3. In a flush tank, a casing, a discharge valve comprising a tubular valve casing secured in the bottom of said tank, valve means to control the flow of liquid through said casing, and a partition member mounted in said valve casing and extending lengthwise thereof and having its upper edge formed in alternately oppositely projecting lugs positioned in the path of flow, whereby noise in said valve is substantially eliminated.

4. In a flush tank, an outlet valve having a discharge passage, and a partition member mounted to extend diametrically across said passage and lengthwise in the line of flow, said partition member having offset lugs alternately arranged along the edge of said partition, and said partition extending crosswise of said discharge passage member and offset lugs substantially eliminating noise when the tank is emptied through said valve.

noise when the tank is emptied through said valve by obstructing the whirling motion of the water.

5. In a flush tank, an outlet valve having a discharge passage, and a partition member mounted to extend diametrically across said passage and lengthwise in the line of flow, said partition member having offset lugs angularly disposed along one edge of said partition and at an angle of substantially sixty degrees to each other, and said partition member and offset lugs substantially eliminating noise when the tank is emptied through said valve.
- 10 15 In testimony whereof I have hereunto affixed my signature.

PHILIP E. MEANEY.
